ROTARY FLEXIBLE SCRUBBING MEMBER
FOR RECEPTACLE WASHING MACHINESGordon W. Johnson, Raytown, Mo., assignor to
Gordon Johnson Company, Kansas City, Mo.,
a corporation of Missouri

Application November 6, 1947, Serial No. 784,494

4 Claims. (Cl. 15—213)

1

This invention relates to new and useful improvements in a rotary, flexible scrubbing member for washers for receptacles, and has particular reference to washers of the power driven type adapted to wash the interior surfaces of open-end receptacles of substantial depth, such as cream and milk cans and the like.

The primary object of the invention is the provision, in a washer for receptacles of the character described, of a scrubbing element comprising a strip of resilient, flexible material fixed at a point intermediate its ends to the end of a rotatable shaft adapted to project axially into the receptacle to be washed, the end portions of said scrubbing element being extendable by centrifugal force when said shaft is rotated to contact and scrub the interior wall surfaces of said receptacle, said scrubbing element adapted by its flexibility to conform to the shape of the receptacle.

A further object is the provision, in a receptacle washer of the class described, of a scrubbing element comprising a flat strip of flexible material having integral scrubbing fingers projecting outwardly from its surfaces.

Other objects are simplicity and economy of construction, ease and efficiency of operation, and adaptability to wash receptacles of a wide variety of shapes and sizes.

With these objects in view as well as other objects which will appear in the course of the specification, reference will be had to the drawings, wherein:

Figure 1 is a side elevation of a receptacle washer embodying the present invention.

Fig. 2 is a front elevation of the washer.

Fig. 3 is an enlarged vertical section taken on line III—III of Fig. 1, showing the washer in operation and with a milk can in operative relationship thereto.

Fig. 4 is a vertical section taken on line IV—IV of Fig. 2, with the parts left in elevation showing the washer at rest.

Fig. 5 is a reduced horizontal section taken on line V—V of Fig. 3, with the milk can removed.

Fig. 6 is an enlarged plan view of the scrubbing element, partially broken away.

Fig. 7 is a fragmentary sectional view taken on line VII—VII of Fig. 6, with parts left in elevation.

Fig. 8 is a sectional view, partially broken away, taken on line VIII—VIII of Fig. 7.

Fig. 9 is a horizontal section taken on line IX—IX of Fig. 7.

2

Fig. 10 is an enlarged horizontal section taken on line X—X of Fig. 3.

Fig. 11 is an enlarged fragmentary section taken on line XI—XI of Fig. 2, showing the foot-operated switch assembly.

Fig. 12 is a fragmentary vertical section taken on line XII—XII of Fig. 11.

Like reference numerals apply to similar parts throughout the several views, and the numeral 10 14 applies to a substantially square tank constructed of sheet metal or other suitable material, said tank being open at the top and having sides 16, front 18, bottom 20, and back 22. Said sides, front, and back are formed at their upper edges to present an outwardly turned flange 24 which serves to support a cover 26 pivotally secured to flange 24 at its rearward edge by means of hinge 28. Said cover is opened when the washer is in use. Sides 16 of said tank extend 20 beneath the bottom 20 thereof and have outwardly turned flanges 30 at the lower edges welded or otherwise rigidly secured to a base plate 32, thus enclosing a space 34 between tank bottom 20 and said base plate. The base plate 25 is supported above the floor by means of a pair of angle irons 36 fixed to the lower surface thereof along its longitudinal edges. Space 34 is closed at its forward end by means of an access door 38 pivotally secured to front 18 of the tank at the lower edge thereof by means of hinge 40.

Base plate 32 extends rearwardly from tank 14. A motor 42 is rigidly secured to a pair of mounting brackets 44, which are in turn rigidly secured to the rearwardly extended portion of said base plate. The shaft 46 of said motor extends vertically downwardly. Said motor is protected by a cover 48, said cover being hingeably secured at its upper end to flange 24 at the rearward edge of tank 14 by means of hinge 50, and positioned at its lower edge by an angle-iron frame 52 fixed to the upper surface of base plate 32.

Pulley 54, rigidly secured to motor shaft 46, is 45 operatively connected by means of belt 56 with pulley 58 rigidly secured to a vertical shaft 60 extending centrally through tank 14 and space 34. Said shaft is supported for rotation at its lower end by a thrust bearing 62 carried by base plate 32, and extends upwardly therefrom through pulley 58, through bearing 64 carried by brackets 66 rigidly secured to base plate 32, through a marine bearing 68 rigidly secured to the outer surface of tank bottom 20, said bearing 55 being adapted to prevent leakage of washing

liquid from the tank around said shaft, through a hole 70 provided therefor in tank bottom 20, and thence upwardly to a point adjacent the top of tank 14. The portion of shaft 60 disposed within tank 14 is formed to present an outwardly projecting helical member 72 having substantially the form of an auger, said helical member extending to a point adjacent the upper end of shaft 60.

Circular tube 74 fits about the auger portion of shaft 60, forming in conjunction therewith an auger conveyor adapted to convey water upwardly through said tube. Said auger rotates freely within said tube. Tube 74 is fitted snugly at its lower end within a short length of heavy pipe 76 rigidly secured to tank bottom 20 by means of threaded flange 78. Said pipe is slotted longitudinally at 80 adjacent its upper end to provide resilience, and is provided with external tapered threads adapted to be engaged by a clamp ring 82 having corresponding internal threads. Thus, when said clamp ring is screwed downwardly, pipe 76 will be contracted to clamp tube 74 tightly. Said tube, thus rigidly supported, provides support for shaft 60 to prevent lateral movement of the upper end of said shaft. A plurality of circumferentially spaced apart holes 84 formed in tube 74 adjacent its lower end, and a plurality of matching holes 86 formed in pipe 76, permit the washing liquid to enter tube 74.

A disc 88 is rigidly mounted axially on shaft 60 adjacent the upper end thereof, and fits rotatably within the upper end portion of tube 74. Said disc is provided with a plurality of circumferentially spaced apart longitudinal slots 90 formed in its peripheral edge, said slots permitting the upward passage of washing liquid past said disc. A collar 92 is rigidly secured to shaft 60 immediately above disc 88, and is provided with a radial flange 94 spaced apart from disc 88, said flange serving to deflect liquid ejected upwardly through slots 90 outwardly in a substantially horizontal plane. A pair of parallel, spaced apart planar members 96 serve as a support for a scrubbing member 98 comprising a flat strip of rubber or other flexible material. Said member is formed to present a lug 100 projecting downwardly therefrom substantially at the midpoint thereof. Said lug is carried between members 96 and a pin 102 projects through said members and said lug. Said pin is secured in place by cotter keys 104. Both the upper and lower surfaces of said scrubbing member are formed to present a plurality of outwardly extending scrubbing fingers 106, the fingers extending from the lower surface thereof being shorter and more widely spaced apart than those projecting from its upper surface, as shown in Figs. 6 and 8.

A carriage 108 for supporting the receptacle being washed comprises a sleeve 110 carried for sliding movement on tube 74, and a bar 112 extending outwardly in opposite directions from said sleeve to points adjacent the side walls 16 of tank 14. The outer end portions of said bar are offset downwardly so that they may pass downwardly below the top of support pipe 76. A cable 114 is fixed to each end of bar 112, and extends upwardly over a pulley 116. Each of said pulleys is carried for rotation on a pin 118 supported by bearings 120 fixed to the outer surfaces of side walls 16, and projects inwardly through slot 122 formed in said side walls, said slots being disposed well above the level of the washing liquid carried in the tank. A counter-

weight 124 is fixed to the outer end of each cable 114 outside of the tank, said counter-weights being enclosed by covers 126 securely attached to side walls 16. Cables 114 are of such a length that when carriage 108 is at the top of its travel, counter-weights 124 rest on flanges 30 of side walls 14.

An electric heater 128 for heating the washing liquid is carried in the bottom of tank 14 so as always to be submerged in said liquid, and is served from an electrical junction box 130 carried beneath tank bottom 20 in space 34. As shown in Figs. 11 and 12, and electrical switch 132 for controlling motor 42 is securely fixed to one of side walls 16 within space 34 adjacent the front of the washer. The control lever 134 of said switch projects outwardly through a slot 136 provided therefor in side wall 16, and is formed at its outer end to present an eye 138. A substantially vertical rod 140 extends through said eye and is loosely secured therein by washers 142 carried by said rod. At its lower end said rod is pivotally secured to the movable end of a foot pedal 144 pivotally secured by hinge 146 to a mounting bracket 148 rigidly secured to flange 30 of side wall 16. A tension spring 150 secured at its lower end to rod 140 at 152, and at its upper end to cover 126 by screw 154, serves to maintain foot pedal 144 normally in its elevated position. A cover 156 secured to side wall 16 by bracket 158 encloses the portion of the switch linkage external to side wall 16. Tank 14 is provided with an angled drain pipe 160 interconnected with said tank through bottom 20 and projecting outwardly through side wall 16, said extended portion having a manually operable control valve 162 connected therewith.

The operation of the washer is substantially as follows. With motor 42 at rest, scrubbing member 98 hangs downwardly as shown in Fig. 4. With washing fluid contained in tank 14, the receptacle to be washed, such as milk can 164, is inverted over the scrubbing element, the mouth portion of said receptacle resting on bar 112 of carriage 108. Normally counter-weights 124 will have somewhat greater weight than the receptacle, so that a slight downward pressure must be exerted on said receptacle to move it downwardly over the scrubbing member. Foot pedal 144 is then depressed to close switch 132 to start motor 42, and said motor, through pulley 54, belt 56, and pulley 58, rotates shaft 60 and scrubbing element 98. Said scrubbing member is thus extended outwardly in a substantially horizontal plane as shown in Fig. 3, to contact the walls of can 164. The end portions of the scrubbing element lie flat along the walls of the can, bringing the scrubbing fingers 106 thereof into close scouring contact with the can. Thus it may be seen that the scrubbing element is adapted to wash receptacles of non-circular and irregular shapes, and of a wide range of sizes. Normally the scrubbing element twists at its end portions so that its upper surface contacts the receptacle. For this reason the fingers 106 are spaced closely to provide a more efficient scrubbing action. The fingers associated with the lower surface of the scrubbing element are shorter and more widely spaced apart so as not to interfere with its normal flexing.

At the same time, water or other scrubbing liquid entering tube 74 through holes 84 and 86 is carried upwardly through said tube by auger 72 associated with shaft 60, discharged through

slots 98 of disc 88, and deflected outwardly by flange 94 of collar 92 to strike the walls of can 164 in the effective zone of scrubbing member 98, thus increasing the efficiency of the scrubbing action. As can 164 is moved upwardly and downwardly on carriage 108, it is apparent that all parts of its interior will be thoroughly scrubbed. The bottom 186 of the can is scrubbed by fingers 196 at the mid-portion of scrubbing member 98. Tank 14, being square, will normally have unoccupied spaces at the corners thereof outside of receptacle 164, thus permitting the operator to reach downwardly into the tank to scrub manually the outside of the receptacle. When the receptacle has been thoroughly scrubbed, the downward pressure thereon is released to permit carriage 108 to be moved upwardly by counterweights 124 and the receptacle is lifted clear of the scrubbing member. Foot pedal 144 normally will be released before the receptacle is lifted off of the carriage, in order to prevent water from being thrown outside of tank 14.

It is apparent that many minor changes of operation and construction could be made without departing from the scope of the invention, and it is therefore desired to be limited only by the scope of the appended claims.

What I claim is:

1. A scrubbing member comprising an elongated panel adapted for mounting intermediate the ends thereof on a rotatable actuating element therefor, said panel being highly flexible whereby the same radiates from the axis of rotation of said element through centrifugal force during rotation of the element, said panel having a pair of opposed faces each provided with a plurality of spaced, integral fingers, there being an appreciably larger number of fingers on one of said faces than on the other face whereby the panel tends to bend in one direction only upon contact of the panel at the ends thereof with a surface to be scrubbed thereby.

2. A scrubbing member comprising an elongated panel adapted for mounting intermediate the ends thereof on a rotatable actuating element therefor, said panel being highly flexible whereby the same radiates from the axis of rotation of said element through centrifugal force during rotation of the element, said panel having a pair of opposed faces each provided with a plurality of spaced, integral fingers, there being an appreciably larger number of fingers on one of said faces than on the other face and the fingers on said one face being longer than the fingers on said other face whereby the panel tends to bend in one direction only upon contact of the panel at the ends thereof with a surface to be scrubbed thereby.

3. A scrubber for use with a machine for washing containers of the type having a neck portion, said scrubber comprising an elongated flexible scrubbing member having a mounting portion intermediate its ends for attachment to a rotatable actuating shaft, said flexible scrubbing member being extended by centrifugal force when the shaft is rotated to engage the inner walls of the container, resilient fingers on the upper surface of the scrubbing member to engage the bottom and side walls of the container during rotation of the shaft and resilient fingers on the under surface of the scrubbing member to engage the top and neck portions of the container upon removal of the scrubbing member from the container during rotation of the shaft.
4. A scrubber for use with a machine for washing containers of the type having a neck portion, said scrubber comprising an elongated flexible scrubbing member having a mounting portion intermediate its ends for attachment to a rotatable actuating shaft, said flexible scrubbing member assuming an inverted U shape for insertion through the neck portion of an inverted container when the shaft is at rest and being extended by centrifugal force when the shaft is rotated to engage the inner walls of the container, resilient fingers on the upper surface of the scrubbing member to engage the bottom and side walls of the container during rotation of the shaft and resilient fingers on the under surface of the scrubbing member to engage the top and neck portions of the container upon removal of the scrubbing member from the container during rotation of the shaft.

GORDON W. JOHNSON.
